1

In the copending patent application, U. S. Serial No. 683,710, now Patent No. 2,530,591, issued November 21, 1950, there is described a circuit-arrangement for the amplification of electrical oscillations by means of at least two parallel-connected discharge paths, controlled by control grids, having characteristic curves the slopes of which vary differently as a function of the control-grid voltage. This circuit-arrangement has the characteristic that use is made of discharge paths, of which one has a comparatively high average mutual conductance and a comparatively small grid space and the other on the contrary has a comparatively low mutual conductance and a comparatively large grid space, provision being made of means which automatically ensure that the amplification, in the case of small amplitudes of the oscillations to be amplified, is effected solely or practically solely by means of the first-mentioned discharge path and in the case of large amplitudes of these oscillations, solely or practically solely by means of the last-mentioned path.

The automatic change-over from one discharge path to the other can effectively be ensured by supplying to the control grids a control voltage varying with the amplitude of the oscillations to be amplified, which voltage blocks the first-mentioned discharge path with comparatively high values of the oscillations to be amplified and which influences at the same time the potential of an auxiliary electrode located in the last-mentioned discharge path (that is the path having the comparatively small average mutual conductance and the comparatively large grid space), in such manner that this path is blocked in the case of comparatively low values of the oscillations to be amplified.

In one form of construction of the circuit-arrangement described in detail, the said auxiliary electrode is connected, via a resistance, to the interconnected anodes of the two discharge paths, whilst the common anode circuit of these paths includes a resistance, preferably high, which is proportioned in such manner that in the case of small amplitudes of the oscillations to be amplified the discharge path including the auxiliary electrode is blocked.

The invention provides an improvement of this circuit-arrangement by which the maximum amplification obtainable is raised. The invention is based on the recognition of the fact that the said resistance interposed between the auxiliary electrode and the anodes reduces the anode impedance and consequently the amplification.

2

According to the invention the auxiliary electrode is connected to an electrode placed in the discharge path having the comparatively high average mutual conductance and extending through a comparatively small part of this discharge path. A positive voltage is applied to the auxiliary electrode through a preferably high resistance, the said electrode and the said resistance being proportioned in such manner that in the case of comparatively small amplitudes of the oscillations to be amplified the discharge path comprising the auxiliary electrode is blocked completely or almost completely.

The auxiliary electrode is preferably connected direct to the aforesaid electrode.

In order that the invention may be clearly understood and readily carried into effect it will now be set out more fully with reference to the accompanying drawing.

20 In the drawing:

Fig. 1 is a schematic diagram of a circuit in accordance with the invention, and

Fig. 2 is a cross-sectional view of the tube included in the circuit of Fig. 1.

25 The drawing illustrates a circuit-arrangement for the amplification of low-frequency oscillations, in which use is made of two discharge paths (A and B), both of which are housed in one discharge tube 1. This tube comprises a control grid 2, a screen grid consisting of two parts 3 and 3', a suppressor grid 4, an anode 5, and a cathode 6 which is connected to suppressor grid 4. The aforesaid auxiliary electrode is formed by parts 3' of the screen grid. The discharge path A which comprises this auxiliary electrode, is controlled by a part of the control grid which is realized with an uneven winding pitch. The part of the control grid located in the other discharge path is wound with a constant pitch. The two control-grid parts are electrically through-connected. The suppressor grid 4, the anode 5 and the cathode 6 serve at the same time for both the discharge paths.

30 The screen-grid part 3 is connected, via a potentiometer constituted by two resistances 7 and 8, to the positive terminal of a supply of direct current voltage (not shown) and, via a condenser 9, to the cathode 6.

According to the invention an electrode 14 is 35 located in the discharge path B, that is the discharge path having the comparatively high average mutual conductance and the comparatively small grid space. The said electrode, which is preferably formed in the shape of a rod, 40 extends through a comparatively small part of

the discharge path B and is connected direct to the auxiliary electrode 3'. The potential of this electrode has little or not influence on the current flowing in the discharge path B. The auxiliary electrode 3' is connected, through a high resistance 10, to the positive terminal of a direct-current voltage supply (not shown). The electrode 14 and the resistance 10 are proportioned in such manner that in the case of comparatively small amplitudes of the oscillations to be amplified the discharge path A is blocked completely or almost completely. The auxiliary electrode 3' is connected to the cathode 6 via a condenser 11. The anode circuit includes a comparatively high resistance 12. The value of resistance 10 is, as a rule, higher than that of resistance 12.

The low-frequency oscillations to be amplified are supplied, together with a control-voltage varying with the amplitude of these oscillations, to the control grid 2. The amplified oscillations can be taken from resistance 12 through a condenser 13.

The circuit-arrangement operates in a manner similar to that of the patent application, heretofore mentioned, i. e. a high maximum noiseless amplification (at a low anode current) when the amplitude of the oscillations to be amplified is comparatively small, and an amplification that is very well adjustable when this amplitude is comparatively large. The high maximum amplification is obtained by means of the discharge path B which comprises the screen-grid part 3, whereas the adjustable amplification is brought about by means of the discharge path A in which the auxiliary electrode 3' is located.

In this case, however, the automatic change-over from one discharge path to the other is effected in a manner different from that in the aforesaid form of the arrangement described in the patent application, heretofore mentioned.

In the case of a large amplitude of the oscillations to be amplified, hence at a high negative value of the control voltage, the right-hand discharge path is blocked by the control voltage supplied to the control-grid 2, whereas the left-hand discharge path keeps operative. In the case of a small amplitude of the oscillations to be amplified, hence at a small negative value of the control voltage, the right-hand discharge path keeps operative, whereas the left-hand discharge path is blocked completely or almost completely.

This blocking takes place as follows: In the case of a decrease of the negative value of the control voltage the current of the right-hand discharge path increases. From this current a small portion is derived by the electrode 14. This portion flows through resistance 10 to the cathode and consequently brings about at this resistance a voltage drop. The electrode 14 and the resistance 10 are proportioned in such manner that the voltage drop is so high that the voltage of the auxiliary electrode falls below the minimum value required to maintain the discharge current, so that the left-hand discharge path is blocked completely or almost completely. In this case the discharge path A consequently contributes to the amplification no longer or substantially no longer.

The present circuit-arrangement has the advantage over the form of the arrangement described in the main patent specification, heretofore mentioned, that the anode impedance may have a high value, since the resistance 10 is no longer connected to the anode 5.

A similar result may be obtained by providing the auxiliary electrode 3' with an extension which extends through a comparatively small part of the discharge path B. In one practical form of construction the auxiliary electrode 3' and the screen grid 3 can, for example, be wound coaxially, the winding of the auxiliary electrode 3', being continued to such an extent that this electrode overlaps a small part of screen grid 3.

10. What I claim is:

1. An amplifying circuit arrangement comprising, first and second thermionic discharge paths enclosed in an evacuated envelope, said paths being connected in parallel relation and having cathodes and anodes connected in common, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode between the control grid and anode of the second thermionic discharge path, a source of desired signals, means to couple said source to the cathode-control grid circuits of the said first and second discharge paths, an electrode inserted between the screen grid and anode of the first thermionic discharge path, and means to couple said latter electrode to the auxiliary electrode whereby the second discharge path is blocked upon the source of desired signals reaching in magnitude a predetermined level.

2. An amplifying circuit arrangement comprising, first and second thermionic discharge paths enclosed in an evacuated envelope, said paths being connected in parallel relation and having cathodes and anodes connected in common, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode between the control grid and anode of the second thermionic discharge path, a source of desired signals, means to couple said source to the cathode-control grid circuits of the said first and second discharge paths, a resistive element, means to apply a source of direct current potential to said auxiliary electrode through said resistive element, and an electrode inserted between the screen grid and anode of the first thermionic discharge path, said latter electrode connected to the auxiliary electrode whereby the second discharge path is blocked upon the source of desired signals reaching in magnitude a predetermined level.

3. An amplifying circuit arrangement comprising, first and second thermionic discharge paths enclosed in an evacuated envelope, said paths being connected in parallel relation and having cathodes and anodes connected in common, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic dis-

5

charge path and an auxiliary electrode between the control grid and anode of the second thermionic discharge path, a source of desired signals, means to couple said source to the cathode-control grid circuits of the said first and second discharge paths, a resistive element, means to apply a source of direct current potential to said auxiliary electrode through said resistive element, and an electrode having the shape of a rod inserted between the screen grid and anode in the first thermionic discharge path, said latter electrode connected to the auxiliary electrode whereby the second discharge path is blocked upon the source of desired signals reaching in magnitude a predetermined level.

4. An amplifying circuit arrangement comprising, first and second thermionic discharge paths enclosed in an evacuated envelope, said paths being connected in parallel relation and having cathodes and anodes connected in common, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode between the control grid and anode of the second thermionic discharge path, a source of desired signals, means to couple said source to the cathode-control grid circuits of the said first and second discharge paths, a resistive element, means to apply a source of direct current potential to said auxiliary electrode through said resistive element, and an extension of the said auxiliary electrode inserted between the screen grid and anode in the first thermionic discharge path whereby the second discharge path is blocked upon the source of desired signals reaching in magnitude a predetermined level.

5. An amplifying circuit arrangement comprising, first and second thermionic discharge paths enclosed in an evacuated envelope, said paths being connected in parallel relation and having cathodes and anodes connected in common, the first thermionic discharge path having further a control grid electrode with given spacing between cathode and anode and given mutual conductance, the second thermionic discharge path having further a control grid electrode with larger spacing between cathode and anode and lower mutual conductance than that of the said first thermionic discharge path and a screen grid electrode comprising of two parts insulated electrically from each other and inserted respectively in the first and second thermionic discharge paths, a source of desired signals, means to couple said source to the cathode control grid circuits of the said first and second discharge paths, a resistive element, means to apply a source of direct current potential to said auxiliary electrode through said resistive element, and an electrode between the screen grid and anode in the first thermionic discharge path, said latter electrode connected to the screen grid electrode in the second discharge path whereby the second discharge path is blocked upon the source of desired signals reaching in magnitude a predetermined level.

6. An amplifying circuit arrangement comprising, first and second thermionic discharge paths enclosed in an evacuated envelope, said paths being connected in parallel relation and

1

having a common cathode and common anode, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode between the control grid and anode of the second thermionic discharge path, a source of desired signals, means to couple said source to the cathode-control grid circuits of the said first and second discharge paths, a resistive element, means to apply a source of direct current potential to said auxiliary electrode through said resistive element, and an electrode inserted between the screen grid and anode of the first thermionic discharge path, said latter electrode connected to the auxiliary electrode whereby the second discharge path is blocked upon the source of desired signals reaching in magnitude a predetermined level.

25 7. An amplifying circuit arrangement comprising, first and second thermionic discharge paths enclosed in an evacuated envelope, said paths being connected in parallel relation and having a common cathode and common anode, the first thermionic discharge path having
30 further a control grid electrode with given spacing between cathode and anode and given mutual conductance and a screen grid electrode, the second thermionic discharge path having further a control grid electrode with larger spacing be-
35 tween cathode and anode and lower mutual conductance than that of the first thermionic dis- charge path and an auxiliary electrode between the control grid and anode of the second therm- ionic discharge path, a source of desired sig-
40 nals, means to couple said source to the cathode- control grid circuits of the said first and second discharge paths, a resistive element, means to apply a source of direct current potential to said auxiliary electrode through said resistive element,
45 and an electrode having the shape of a rod in- serted between the screen grid and anode of the first thermionic discharge path, said latter elec- trode connected to the auxiliary electrode where- by the second discharge path is blocked upon the
50 source of desired signals reaching in magnitude a predetermined level.

55 predetermined level.

8. An amplifying circuit arrangement comprising, first and second thermionic discharge paths enclosed in an evacuated envelope, said paths being connected in parallel relation and having a common cathode and common anode, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode between the control grid and anode of the second thermionic discharge path, a source of desired signals, means to couple said source to the cathode-control grid circuits of the said first and second discharge paths, a resistive element, means to apply a source of direct current potential to said auxiliary electrode through said resistive element, and an extension of the said auxiliary electrode inserted between the screen grid and anode of the first thermionic discharge path, said latter elec-

trode connected to the auxiliary electrode whereby the second discharge path is blocked upon the source of desired signals reaching in magnitude a predetermined level.

9. An amplifying circuit arrangement comprising, first and second thermionic discharge paths enclosed in an evacuated envelope, said paths being connected in parallel relation and having a common cathode and common anode, the first thermionic discharge path having further a control grid electrode with given spacing between cathode and anode and given mutual conductance and a screen grid electrode, the second thermionic discharge path having further a control grid electrode with larger spacing between cathode and anode and lower mutual conductance than that of the first thermionic discharge path and an auxiliary electrode wound coaxially with the screen grid electrode in the first discharge path and between the control grid and anode of the second thermionic discharge path, a source of desired signals, means to couple said source to the cathode-control

grid circuits of the said first and second discharge paths, a resistive element, means to apply a source of direct current potential to said auxiliary electrode through said resistive element, and an extension of the said coaxially wound auxiliary electrode inserted in the first thermionic discharge path whereby the second discharge path is blocked upon the source of desired signals reaching in magnitude a predetermined level.
